EARLE M. WOODEN, OF NEW YORK, N. Y., ASSIGNOR TO THE PERFECTOGRAPH MANUFACTURING COMPANY, OF NEW YORK, N. Y., A CORPORATION OF DELAWARE.

SAFETY DEVICE FOR MOVING-PICTURE MACHINES.

1,149,609.

Specification of Letters Patent.

Patented Aug. 10, 1915.

Application filed July 18, 1914. Serial No. 851,697.

To all whom it may concern:

Be it known that I, EARLE M. WOODEN, a citizen of the United States, residing in the borough of Manhattan of the city of New York, in the State of New York, have invented certain new and useful Improvements in Safety Devices for Moving-Picture Machines, of which the following is a specification, reference being had to the accompanying drawings, forming a part hereof.

In accordance with general practice the prime mover for operating the mechanism of moving picture machines is usually set in motion and stopped by the operator through positive movement of a suitable controlling switch or its equivalent. In other words, after the mechanism has once been set in motion by throwing the control handle, the operator is free to leave the machine until the entire film has been exhibited. Oftentimes, while the film is being run through the machine, one portion of it becomes overheated and burns, or derangements of some portion of the mechanism occur, making it desirable for the operation of the machine to be stopped instantaneously. In case of the burning film, for instance, if the arc is not extinguished at once, a serious blaze might ensue and the audience be disturbed by such an alarming interruption. In the case of derangements of some of the parts of the mechanism, the continued application of power through the prime mover might result in very serious and permanent injury to the film.

In order to overcome the dangers referred to, the present invention has for its principal object the provision of a safety device which shall control the operation of the mechanism of moving picture machines and which shall require the constant attention of the attendant and continued application of physical effort on the part of the attendant for the operation of the machine.

In accordance with the invention a control handle is provided which controls the arc of the lamp as well as the operating mechanism of the machine and which must be held in predetermined position by the attendant so long as the arc is lighted and the mechanism of the machine is operating. If this switch is released by the operator it is returned to its normal position of rest and simultaneously breaks the circuit of the arc

and brings about the stoppage of the operating mechanism.

As this description proceeds it will be evident that the objects expressed above may be accomplished by widely diversified embodiments of the invention, the structure shown in the accompanying drawings serving to illustrate merely one way in which the invention may be realized.

In these drawings Figure 1 is a fragmentary view, partly in side elevation and partly in section, of so much of a moving picture machine as is necessary for a complete description of the application of the improved devices thereto. Fig. 2 is a view in section taken on the plane indicated by the line 2-2 of Fig. 1 and looking in the direction of the arrows, and showing particularly the relationship of the improved controlling switch, the prime mover and the film base. Fig. 3 is an enlarged fragmentary detail view of the controlling switch. Fig. 4 is a view on the same scale as that of Fig. 3 showing the controlling switch and a fragment of its connection with the prime mover. Fig. 5 is a fragmentary view taken on the plane indicated by the line 5-5 of Fig. 4 and looking in the direction of the arrows.

As shown in Fig. 1, the improved devices may be used in conjunction with a moving picture machine of the usual type, including a lamp house *a* mounted on a base *b*, the lamp house having mounted therein the usual carbons for throwing the projecting beam, the carbons deriving their current through suitable leads *c* and *d*, in the circuit of which may be disposed a controlling switch *c'* of any usual form. On the base *b* may be mounted, as through standards *e*, a housing *e'* on which is carried a reel, indicated conventionally at *e''*, it being understood that the film itself (not illustrated) passes from the reel *e''* to a suitable wind-on reel, indicated generally at *f*, past an aperture *e³* formed in the rear wall of the housing *e'*, to permit the images on the film to be projected successively through the lens *e⁴* on to the usual exhibiting screen. It has been deemed unnecessary to illustrate the usual shutter for cutting off the images from the screen momentarily as the film is moved forward, and other well known mechanism, such as that for driving the wind-on reel *f*, since such devices are common in the art.

and their illustration would not be conducive to a clearer understanding of the subject matter of this application. It is to be understood, however, that all such necessary operating mechanism, as well as some portions of the improved devices, may be operated by a prime mover, indicated herein as an electrical motor g . If desired, this motor may run continuously or suitable connections may be made with the improved controlling mechanism or an independent switch, for starting and stopping it when desired. At all events, in the illustrated embodiment, the armature shaft of the motor g carries thereon a disk g' having a conical face, for purposes to be mentioned later. In juxtaposition to the disk g' is mounted a shaft h having its axis preferably disposed angularly with respect to the axis of the armature shaft of the motor g , this shaft h being termed hereinafter the prime mover shaft, since in the illustrated embodiment, it is this shaft which transmits power to the machine and is alternately stopped and started through the control of the improved switch, for the purpose of operating the machine.

From the description thus far given, it is believed that the application of the improved devices to the usual and well known elements referred to, will be readily understood. The improved controlling switch is illustrated as a lever i provided with an operating handle i' and mounted on an oscillatory shaft i^2 , journaled in suitable brackets b' and b^2 carried by the frame b of the lamp house. On the front face of the bracket b' is formed a quadrant-like segment b^3 , having at one end a shoulder b^4 , with which may engage a spring-pressed latch i^3 mounted operatively on the rear side of the controlling lever i and connected with the handle i' , whereby the latch may be swung out from the shoulder b^4 by pressing the handle i' inward, so as to release the lever i and permit it to be swung across the face of the segment b^3 for a purpose which will appear hereinafter. The lever i is normally maintained with the latch i^3 in engagement with the shoulder b^4 , by the action of a spring k which is anchored at one end to the bracket b' and at the other end to the lever. The free end of the shaft i^2 is provided with spiral threads, indicated at i^4 , which are in operative engagement with an interiorly threaded collar l which may have formed integral therewith a yoke l' in engagement with a grooved sleeve m feathered on the prime mover shaft h as by means of a slot h' and spline n . One end of the sleeve m is formed with a circular flange m' , the edge of which may be moved into driving engagement with the conical face of the disk g' on the armature shaft of the prime mover g . By inclining the axis of the disk g' with

respect to the shaft h it will be evident that the conical face of the disk may be disposed in a plane parallel to the flat edge of the circular flange m' , and in this way the flange may be moved with the sleeve along the shaft h from the position illustrated in Fig. 2 to engage effectively with the face of the disk, as shown in Fig. 4. One of the features of the invention resides in the provision of devices whereby this movement of the sleeve m and flange m' , into and out of driving engagement with the motor disk g' , may be readily effected. From the description given of the controlling handle and the movement of the sleeve m , which it is sought to secure, it will be appreciated that when the handle i' is moved inward, the latch i^3 is tripped to release it from engagement with the shoulder b^4 and permit the lever i and the threaded shaft i^2 to be rocked in a clockwise direction. This rocking movement brings about an axial movement of the sleeve l , by reason of its threaded engagement with the shaft i^2 , and in turn results in a sliding movement of the sleeve m along the prime mover shaft h , to the right, as viewed in Fig. 4, thus clutching the prime mover shaft h with the rotating motor disk g' , through the flange m' and spline n and thereby initiating operation of the mechanism of the machine. In effecting this clutching engagement, it will be noticed that the speed of rotation of the shaft h is determined by the radial distance between the armature shaft and the point of contact of the flange m' with the face of the disk g' and the point of engagement of the flange with the disk depends upon the extent of movement of the lever i by the operator, across the face of the segment b^3 . In considering the reverse movement of the lever i , it will be appreciated that when the operator releases the handle i' , the spring k will be effective to restore the lever to its normal position, thus rocking the shaft i^2 in a counter clockwise direction and bringing about an axial movement of the sleeve m to the left, as viewed in Fig. 4, and a disengagement of the flange m' from the face of the motor disk g' . Such disengagement, of course, results in immediate stoppage of all portions of the mechanism which are driven by the prime mover g . To insure the quick stoppage of rotation of the shaft h and prevent continued operation of the various mechanism driven therefrom, after release of the handle i' and the lever i by the operator, the lever is provided on its rear face with a stud i^5 which may extend through an arcuate slot b^5 formed in the bracket b' and engage a suitable brake band b^6 supported pivotally on the upper end of the bracket b' and arranged to embrace a suitable braking face h^2 which may be provided in the form of a

collar secured to the shaft h . Normally the 5
brake b^6 is held out of engagement with the
braking face h^2 by a spring b^7 operatively
interposed between the free end of the band
and a fixed anchorage on the bracket b' .
When the lever i is moved to its normal
position of rest under the influence of the
spring k , the stud i^5 is drawn into engagement
10 with the free end of the brake band
 b^6 so as to move the latter into braking
engagement with the collar h^2 on the shaft h ,
against the action of the relatively weak
spring b^7 , thus affording an effective means
for overcoming the inertia of the rotating
15 shaft h and its associated parts and insuring
the quick stoppage thereof.

One of the principal features of the 20
invention, as indicated in the preamble to this
specification, resides in the provision of
means for cutting off the source of light
whenever, for any reason, the attendant
25 releases the controlling lever i . It will be
understood that such release will probably
ensue whenever the operator becomes inattentive
or unmindful of the operation of the
30 machine or whenever the mind of the operator
is under stress, as when some derangement
of the mechanism occurs or when a
portion of the film catches fire. It is at such
35 times that it is desirable for the operation
of the machine to be cut off automatically,
and the present devices remove the control
of the machine from the operator to the ex-
tent that its operation will be stopped auto-
40 matically whenever the handle is released.
In order to cut off the light a very simple
mechanical movement is provided in the
illustrated embodiment whereby, when the
45 lever is drawn to its normal position, with
the toe of the latch i^3 against the shoulder b^4 ,
the toe will engage the tail of an elbow lever
 o , the other arm of which is connected op-
eratively to a latch p , as through a link p' ,
50 which in turn engages with a hook c^2 car-
ried by the controlling switch c' in the cir-
cuit c of the arc light. This switch c' is
moved to close the circuit c against the ac-
tion of a spring c^3 , so that when the latch p
55 is rocked to disengage itself from the hook
 c^2 , the spring c^3 is effective to withdraw the
switch from its operative position and break
the circuit of the arc light. For holding
the latch p in engagement with the hook c^2 ,
the link p' or any other portion of the con-
60 nection between the lever o and the latch
may be subjected to the action of a spring
 p^2 . It will now be understood that when the
nose of the latch i^3 rides down the shoulder
 b^4 , it will engage the tail of the lever o
65 and rock the same so as to release the latch p
from engagement with the hook c^2 and
bring about the interruption of the arc light
circuit c . On the other hand, if the operator
desires, for any reason, to stop the
65 operation of the mechanism of the moving

picture machine and yet permit the beam
of light to remain, the lever i may be moved
in a counter clockwise direction to its nor-
70 mal cut-off position and the latch i^3 be held
retracted by pressure on the handle i' , as
will be understood. In this way, the nose
of the latch i^3 is not permitted to ride down
the shoulder b^4 and engage the lever o , the
result being that the switch c' is not released
in the manner described. 75

The sliding movement of the shaft r with
the sleeve q' in one direction is made against
the action of a spring r' which encircles the
shaft r and is interposed between the sleeve
 q' and the housing e' . The shutter q is ar-
ranged to have an oscillating movement
so about the shaft r , the extent of such move-
ment being between the positions indicated
in dotted lines in Fig. 6 and that indicated
by full lines in the same figure, and being
determined by a slot and stud connection
85 indicated generally at q^2 between the sleeve
 q' and the shaft r . One end face of the
sleeve q' carries a stud q^3 arranged to reg-
ister and engage with a recess s formed in
90 the end face of a second sleeve s' supported
rotatably on the shaft r .

During the normal operation of the 95
machine the shutter q is held in its elevated
position, out of the path of the projected
beam, by devices now to be described. In
one portion of the housing e' , which may
be separated from the shutter q , and so much
of its mechanism as is connected directly
thereto, by means of a vertical partition e^6 , 100
is arranged a collar t fixed on a shaft t'
which may be journaled slidably in the wall
of the housing e' and may be provided with
steep threads, indicated at t^2 , with which en-
gage corresponding threads formed on the in-
terior of the collar t . This collar is held against
axial movement by means of a suitable
105 bracket e^7 carried on the wall of the housing
 e' and beneath this bracket is arranged a sec-
ond collar t^3 fixed to the shaft t^2 and engaged
loosely by the upper ends of weighted gov-
ernor arms u adapted to be rotated by means
of power derived from the prime mover
shaft h and transmitted to the govern-
110 or arms through such elements as a pulley h^3 ,
stub shaft e^8 journaled in the housing e' ,
and intermeshing beveled pinions e^9 and u
carried respectively by the shaft e^8 and the
governor arms. When the prime mover
shaft h is rotated by the engagement of the 115
flange m' with the face of the motor disk
 g' , the governor arms u are rotated and the
centrifugal force thereon will serve to draw
their free upper ends downward with the
collar t^3 and shaft t' . Axial movement of
the shaft t' in this manner will serve to ro-
tate the sleeve t through its engagement
with the threads t^2 . The sleeve t carries an
arm t^4 , which rests in a slot v formed in an
arm v' carried on an oscillatory sleeve v^2 120
125

which may be journaled in the partition e^6 and connected operatively with the sleeve s' on the shaft r through suitable links w , one of which w' , is secured to the sleeve s' at such a distance from its axis as to facilitate its oscillation about the shaft r .

From the description thus far given, it will be evident that during the normal operation of the machine the arm t^4 is held in such angular position by the action of the governor arms u and associated parts on the collar t , that the sleeve s' and the sleeve q' are held in such angular position with respect to the shaft r as to maintain the shutter q in a position out of the path of the projecting beam, as indicated in dotted lines in Fig. 6. In order to permit the shutter q to drop in the path of the projecting beam when the controlling lever i is released, it has been found convenient, in the illustrated embodiment, to fix the lever o on a rock shaft x on which is secured an arm x' secured to a reciprocable rod y , as through a link x^2 , which reciprocable rod may be mounted slidably in brackets e^{10} supported on the reel base e . On the rod y is supported in a substantially vertical position an arm y' , on the upper end of which is formed a yoke y^2 adapted to engage operatively with the sleeve q' . It will now appear that when the lever i is moved to its normal position of rest under the action of the spring k so that the toe of the latch i^3 rocks the lever o in the manner described, the rock shaft x will serve to draw the rod y to the left, as indicated in Fig. 1, and through the engagement of the arm y' with the sleeve q' , move the latter against the action of the spring r' and disengage the stud q^3 from the recess s . As soon as this disengagement is effected, the shutter q is free to drop under the influence of gravity until checked in its movement through the slot and stud connection q^2 of the sleeve q' with the shaft r . This slot and stud connection is such as to check the shutter q when it is directly in the path of the projecting beam. Simultaneously with the movement of the sleeve q' the sleeve m is slid along the shaft h to disengage the flange m' from the face of the drive disk g' and stop the operation of the mechanism driven from the shaft h including the short shaft e^8 by which the governor arms u are rotated. When rotation of the governor arms u ceases a suitable spring u^2 restores the arms to their normal position and moves the shaft t' axially, such movement of the shaft resulting in partial rotation of the sleeve t and movement of its arm t^4 to its normal position of rest. Such movement of the arm t^4 will bring about a corresponding movement of the links w and result in partial rotation of the sleeve s' about the shaft r , the extent of this rotation being such that the recess s will be brought

into line with the stud q^3 on the sleeve q' . The next succeeding movement of the controlling lever i by the operator to initiate movement of the operating mechanism will serve to release the rod y and arm y' and permit the spring r' to move the stud q^3 into the recess s . Simultaneously with this clutching engagement rotation of the governor arms u is brought about and the shutter q is raised out of the path of the beam of light, in the manner hereinbefore described.

From the detailed description of the parts and the brief outline of their mode of operation given in connection with such description, it is believed that their coördinate operation will now be understood. It should be noted, particularly, however, that while all of the mechanism described is interrelated, it lies within the scope of this invention to employ one or more of the improvements illustrated as conditions of use require. Moreover the specific structures employed for bringing about the desired results may be changed by those skilled in the art, but all such changes are to be deemed within the scope of this invention provided they fall within the terms of the claims appended.

I claim as my invention:

1. In a moving picture machine, the combination with the source of electrical energy for the projecting light, of a switch to control the electrical circuit, devices for holding the switch in closed position during the projection of the images, and a manually operable lever operatively positioned with respect to such last named devices, whereby when the lever is in its normal position the said devices are positioned to open the switch, and when the lever is moved out of its normal position by the operator the switch may be closed.

2. In a moving picture machine, the combination with the operating mechanism and the source of electrical energy for the projecting light, of a switch to control the said circuit, devices for holding the switch in closed position during the projection of the images, a manually operable lever operatively positioned with respect to said last named devices, and means carried by said lever for controlling the operating mechanism, whereby when the lever is in its normal position the switch is open and the operating mechanism is inactive, and when the lever is moved by the operator out of its normal position the switch may be closed and movement of the operating mechanism is initiated.

3. In a moving picture machine, the combination with the operating mechanism and the source of electrical energy for the projecting light, of a switch to control the said circuit, devices for holding the switch in

closed position during the projection of the images, a manually operable lever operatively positioned with respect to said last named devices, means carried by said lever 5 for controlling the operating mechanism, whereby when the lever is in its normal position the switch is open and the operating mechanism is inactive, and when the lever is moved by the operator out of its normal 10 position the switch may be closed and move-

ment of the operating mechanism is initiated, and means to restore the lever to its normal position automatically whenever it is released by the operator.

This specification signed and witnessed 15 this 17th day of July A. D. 1914.

EARLE M. WOODEN.
